UNITED STATES PATENT OFFICE.

DOROTHY M. LANDER, OF CHICAGO, ILLINOIS.

DESIGN FOR A HAND-BAG.

48,497.

Specification for Design.

Patented Feb. 1, 1916.

Application filed August 30, 1915. Serial No. 48,125. Term of patent 3½ years.

To all whom it may concern:

Be it known that I, DOROTHY M. LANDER, a citizen of the United States, residing at Chicago, in the county of Cook and State of Illinois, have invented a new, original, and ornamental Design for Hand-Bags, of which the following is the specification, reference being had to the accompanying drawing, forming part thereof.

In said drawing, the figure is a perspective view of a lady's hand bag, showing my present design applied thereto.

I claim:

The ornamental design for a hand bag, as shown.

DOROTHY M. LANDER.
